OR D 11,320

No. 11,320

August 5, 1879

UNITED STATES PATENT OFFICE.

AUGUST WERNER, OF NEW YORK, N. Y.

DESIGN FOR FOUNTAINS.

Specification forming part of Design No. **11,320**, dated August 5, 1879; application filed July 8, 1879.
[Term of patent 3½ years.]

To all whom it may concern:

Be it known that I, AUGUST WERNER, of New York city, county and State of New York, have invented a new and original Design for Fountains, of which the following is a specification.

The accompanying photographic illustration represents a side elevation of my newly-designed fountain.

This invention relates to a new and original design for fountains or other structures; and consists in the new configuration of the superstructure, as hereinafter more fully pointed out.

In the photographic illustration, the letter A represents the base or pedestal of the fountain or support of my design. Upon the same is arranged a superstructure in form of an irregular pyramid, composed of blocks or pieces

of glass or other transparent or translucent material. On this pyramid are grouped a series of bottles or bottle-shaped ornaments, b.

One bottle or bottle-shaped ornament placed upon the apex of the pyramid a may serve as the discharge-pipe for the jet of the fountain, as shown.

I claim—

1. The design for the superstructure of a fountain or pedestal, consisting of the irregular pyramid a and of the bottle-shaped ornaments b, substantially as shown.

2. The design for a fountain, consisting of a base, A, and irregular glass pyramid a, having ornaments b, substantially as shown.

AUG. WERNER.
